UNITED STATES PATENT OFFICE.

JOHN F. HOYT, OF NEWINGTON, NEW HAMPSHIRE.

BREAD-CUTTER.

1,274,551.

Specification of Letters Patent.

Patented Aug. 6, 1918.

Application filed June 6, 1916. Serial No. 102,030.

To all whom it may concern:

Be it known that I, JOHN F. HOYT, a citizen of the United States, residing at Newington, State of New Hampshire, have invented certain new and useful Improvements in Bread-Cutters, of which the following is a specification.

This invention relates to cutlery, and has more especial reference to an improved cutting device for slicing loaves of bread, meat, vegetables, etc. It is primarily sought by the invention, to provide a device of the character stated whereby, a loaf of bread may be readily sliced, the slices being of a uniform thickness; further, a cutting device which may be used for cutting or chopping meats, vegetables and the like.

Another important characteristic of the invention resides in the mounting of the cutting knife so that the same can be moved both longitudinally and vertically, whereby to permit of the ready cutting of the desired matter.

The invention also aims to provide a novel cutting device, portable in character, easily manipulated, strong and durable in use, and one which might be manufactured at a minimum cost, due to the extremely simple construction thereof.

The improvements in the detail and arrangement of parts will be apparent from an inspection of the accompanying drawings, in connection with the specific description hereinafter contained, and wherein the preferred embodiment of the invention is disclosed for the purpose of imparting a full understanding of the invention.

In the drawings:

Figure 1 is a longitudinal section through the device showing the mounting of the cutting knife, and

Fig. 2 is a fragmental top plan.

Referring to the drawings in detail, which illustrate the preferred embodiment of the invention and in which like reference characters designate corresponding parts throughout the several views, I provide a base or body portion, which is indicated by the numeral 1. A portion of the base 1 is recessed as at 2, providing an inclined guideway the purpose of which will be subsequently apparent. Positioned within suitable seats formed upon the upper surface of the base 1 and adjacent the side walls of the recessed portion 2, are metal strips 3 and 3'. A plurality of openings are formed within

the metal strips 3 and 3' and have passed therethrough into engagement with the base 1, nails or other suitable fastening devices, shown at 4. Angular supporting posts 5 and 5' are in turn, secured to the adjacent extremities of the strips 3 and 3' through the medium of rivets or the like 6. The upright portions of the supporting posts carry bearings 7 whereby the supporting roller 8 may be journaled therein. It is to be also noted that the posts 5 and 5' are positioned in proximity to the upper portion of the inclined recess 2.

A knife 9 having a handle part 10 and provided with an elongated slot 11, which slot is formed within the back of the knife and extends substantially throughout the entire length thereof, slides upon the roller 8. Thus, it will be apparent, that when the roller 8 is positioned within the elongated slot 11 of the knife, that element will be permitted to travel both longitudinally and vertically, and by so doing will facilitate the cutting of such matter as arranged therebelow.

To operate the device and assuming that a loaf of bread is placed upon the base 1 as shown in dotted lines in the Fig. 1, the knife is first raised or swung to a position above the bread loaf as clearly shown in dotted lines in this figure. The knife is then moved downwardly and outwardly to provide for the necessary shearing action of the knife, this position also being shown in dotted lines, and, is then retracted and forced farther downwardly until the desired slice has been severed from the loaf. Should the operator desire to use the device as a vegetable or meat chopper, it is evident, that the knife might be raised a suitable distance, the roller 8 serving as its point of fulcrum, and then moved into engagement with the matter.

The device may be readily disassembled, by removing the bearings 7 from their respective upright supporting posts and, the parts may be then cleaned or replaced and then assembled.

It is of course, to be appreciated, that any form of knife may be used, such as conditions or preference may dictate, the usual bread cutting knife being substituted for the one as employed in this embodiment. If so desired, the elongated groove may be eliminated and the knife may be provided with flanged guideways, arranged upon

either side thereof into which the supporting and guide rollers, similar to the roller 8, may be passed.

It will also be noted, by referring to the 5 manner in which the knife 9 is mounted upon the roller 8, that the knife may also be moved laterally when desired, thereby decreasing or increasing the size or maintaining an even size of the slices of bread being cut.

While I have herein described, a specific embodiment of the invention, it will be apparent to persons skilled in the art, that the 15 invention is capable of still further embodiment than those herein especially referred to, as may be in keeping with the hereto appended claims.

Having thus described the invention, what is claimed is:—

20 1. In a device of the class described, the combination of a supporting means, a supporting roller carried by said supporting means, said supporting roller being elongated, a knife having an elongated slot formed therein, said roller projecting through said slot, whereby said knife may be reciprocated and tilted for movement over said roller when desired, said roller being considerably longer than the breadth of

said knife, thus allowing unrestricted side 30 movement of said blade when desired.

2. In a device of the class described, the combination of a base having a diagonal recess formed in one end thereof, strips fixedly mounted upon said base in alignment 35 with the sides of said recess, supporting posts carried by said strips, bearings carried by the upper portions of said posts, a roller carried by said bearings, a knife having a handle thereon, said knife being provided with an elongated slot, said roller projecting through said slot, said roller being comparatively longer than the breadth of 40 said knife, whereby said knife may be reciprocated by movement over said roller, said recess permitting the knife to be tilted in one direction, and said roller permitting side movement of the knife when necessary without the knife encountering interference 45 throughout its movement for the length of 50 said roller.

In testimony whereof I affix my signature in presence of two witnesses.

JOHN F. HOYT.
